CLAIM

The ornamental design for a mat for developing hand-
to-eye coordination in infants, as shown and described.

DESCRIPTION

FIG. 1 is a top perspective view of a mat for developing
hand-to-eye coordination in infants showing my new
design;

FIG. 2 is an end elevational view thereof, the opposite
end being a mirror image of that shown, except for the
air valve;

FIG. 3 is a side elevational view thereof, the opposite
side being a mirror image of that shown, except for the
air valve;

FIG. 4 is a top plan view thereof; and,

FIG. 5 is a bottom plan view thereof.

FIG.1

FIG.2

FIG.3

FIG.4
